Specification for Design.

Patented July 15, 1913.

Application filed March 20, 1913. Serial No. 755,807. Term of patent 3½ years.

To all whom it may concern:

Be it known that I, JOSEF DORNBUSCH, a subject of the King of Prussia, and a resident of the city of Crefeld, Germany, and whose post-office address is Mariannenstrasse 38, have invented a new and original and ornamental Design for Textile Fabrics, of which the following is a specification, reference being had to the accompanying drawing, forming a part thereof.

The figure is a plan view of a portion of the textile fabric, showing my new design.

I claim:

The ornamental design for a textile fabric, as shown.

Signed at the city of Aix-la-Chapelle, Prussia, this 26th day of February, 1913.

JOSEF DORNBUSCH.
